UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed June 14, 1924. Serial No. 719,934.

This invention aims to provide an improved separable fastener.

In the drawings, which illustrate a preferred embodiment of my invention:

5 Figure 1 is a front elevation of the preferred form of fastener;

Fig. 2 is a section on the line 2—2 of Fig. 1, being partly in elevation;

10 Fig. 3 is a section similar to Fig. 2, showing the relation of the parts of the stud when being unlocked from the socket;

Fig. 4 is a section similar to Fig. 2, showing the relation of the parts of the stud when the head is being entered into the stud-15 receiving aperture;

Fig. 5 is a section on the line 5—5 of Fig. 2;

20 Fig. 6 is a section on the line 6—6 of Fig. 2; and

25 Fig. 7 is a section on the line 7—7 of Fig. 2.

Referring to the drawings and to the preferred form of my invention, as illustrated, I have shown a socket 1 including a stud-25 receiving aperture, sealing means, and an attaching screw 2 for attaching the socket to the body 3 of an automobile, substantially as illustrated and described in the co-pending application of Andrew G. Anderson, Serial No. 708,724.

30 The stud may be secured to the curtain 4 of an automobile in any suitable manner, but I prefer to provide a back plate 5, located upon that side of the curtain nearest the socket, presenting a plurality of attaching prongs 6 which pass through the curtain 4 and are clenched preferably outwardly and downwardly by a clenched plate 7 located upon the opposite side of the curtain. This clenched plate also presents an elongated aperture 8, the purposes of which are more fully hereinafter described.

35 The preferred form of socket-engaging means includes a socket-engaging member presenting a head 9 having a neck 10 for engagement with the socket and a locking member 11 slidably mounted within the head and presenting a fin-like part 12 through a longitudinal slot 13 located in the head di-40 metrally opposite the neck 10. This locking member is normally urged forward by a spring 14 interposed between one end of the locking member 11 and the inner face of a cap 15, which fits over the end of the

socket-engaging member, thereby holding 55 the spring in place and presenting a finished appearance to the stud when assembled to the curtain, as illustrated in Fig. 1.

To permit relative tipping movement between the clenched plate 7, curtain 4 and back plate 5 as a unit or casing and the socket-engaging means, I have provided a substantially deep recess 16 in the head 9 which is adapted to receive the pivot 17 located on the back plate adjacent the top of the preferably rectangular aperture 18 in the back plate through which the head passes. This pivot is provided by a reversely bent portion which presents a smooth rounded surface for cooperation with the recess 16. The wall at 70 the bottom side of the aperture presents a reversely bent edge for normal engagement with the fin-like part 12 of the locking member and also for engagement with the depending finger 19, when the back plate is 75 pivoted relative to the socket-engaging means, as more fully hereinafter described.

Assembly of the parts of the stud is as follows. The socket-engaging head 9 is first entered through the aperture 18 in the back 80 plate 5 until the recess 16 is opposite the pivot 17 and the locking member 11 is then placed in the head 9 with the fin-like part 12 projecting through the slot 13. When pushed forward, the fin-like part engages 85 the periphery of the rectangular aperture 18 diametrically opposite the pivot 17 and urges the pivot into the recess 16, thus holding the back plate and head together as illustrated in Figs. 2, 3 and 4. Next the 90 spring 14 is placed in the socket-engaging member and the cap is driven over the outside of the socket-engaging member, thereby holding all of the above-mentioned parts in place prior to assembly thereof to a 95 curtain.

The stud may be secured to the socket by pressure upon the cap, which projects through the elongated aperture in the clenched plate, thus urging the head 9 of the stud 100 into the stud-receiving aperture, and, as best illustrated in Fig. 4, the cam-shaped end 20 of the locking member contacts with the edge of the socket adjacent the periphery of the stud-receiving aperture, thus holding the locking member out of the aperture until the head 9 has passed therethrough and the neck has been engaged therewith. The

spring 14 then urges the locking member forward and the socket-engaging member shifts relative to the stud-receiving aperture to engage the neck thereof with the periphery of the stud-receiving aperture, thereby to permit engagement of the fin-like part 12 of the locking member with the stud-receiving aperture, as best illustrated in Fig. 2. When in the position illustrated in this figure, the stud is locked with the socket against separation from above or at both sides of the socket. Thus a three-side lock fastener is provided which can only be separated by a pull at a predetermined side of the stud.

The stud may be separated from the socket by grasping the lower edge of the curtain and exerting a slight outward pull thereon, which causes the back plate and clench plate or casing to tip about the pivot 17 relative to the socket-engaging member. Thus the reversely bent portion of the back plate adjacent the fin-like part 12 engages the depending finger 19 and moves the locking member relative to the socket-engaging member until the cam-shaped portion 20 is adjacent the periphery of the stud-receiving aperture, as best illustrated in Fig. 3.

Then as a further pull is exerted upon the curtain, the socket-engaging means may tip relative to the socket and become disengaged therefrom. This relative tipping movement between the clench plate and the outer end of the socket-engaging member is permitted by the elongated slot provided in the face of the clench plate. Thus the first part of the tipping action releases the locking member so that the last part of the tipping action tips the socket-engaging head out of engagement with the socket.

While I have shown and described a preferred form of one embodiment of my invention, it will be understood that changes involving omission, alteration, substitution and reversal of parts, and even changes in the mode of operation, may be made without departing from the scope of my invention which is best defined in the following claims.

50 I claim:

1. A stud for a separable fastener including a socket-engaging member, locking means assembled with said socket-engaging member and movable relative thereto for locking said member with a socket and stud-supporting means pivoted upon said socket-engaging member and shiftable relative thereto for moving said locking means into unlocked position to permit separation of said stud from a socket.

2. A stud for a separable fastener including a socket-engaging member presenting a neck for engagement with the wall at one side of a stud-receiving aperture, an axially shiftable spring-pressed locking member as-

sembled with said socket-engaging member and presented through a slot in said socket-engaging member at the opposite side thereof from said neck and an unlocking part pivoted upon said socket-engaging member to shift said locking member relative to said socket-engaging member and permit separation of said fastener.

3. A stud for a separable fastener including a casing secured to a flexible stud-carrying fabric, a socket-engaging member pivotally mounted in said casing and extending therefrom for engagement with a socket, a spring-pressed locking member assembled with said socket-engaging member and presented at one side thereof for locking said socket-engaging member with a socket, said locking member being operable by a pull at a predetermined side of said stud to engage a portion of said casing with a portion of said locking member, thereby to move said locking member relative to said socket-engaging member.

4. A separable fastener comprising, in combination, a socket presenting a stud-receiving aperture, a cooperating stud having a socket-engaging part presenting a neck for engagement with a wall surrounding said aperture, axially movable locking means assembled with said socket-engaging part for engagement with the wall at one side of said aperture to hold said socket-engaging part in locking engagement with a socket, and an unlocking part pivoted to said stud for manipulation of said locking means.

5. A separable fastener comprising, in combination, a socket presenting a stud-receiving aperture, a cooperating stud having a socket-engaging part presenting a neck at one side to provide a shoulder for engagement with a wall surrounding said aperture, spring-pressed axially movable locking means operable within said stud and projecting through the side thereof opposite said neck for engagement with the wall surrounding a stud-receiving aperture to lock said stud against accidental separation from said socket, and an unlocking part assembled with and movable relative to the socket-engaging part for manipulating the locking means to permit separation of the fastener.

6. A separable fastener comprising, in combination, a socket presenting a stud-receiving aperture, a cooperating stud having a socket-engaging part presenting a neck for engagement with a wall surrounding said aperture, axially movable spring-pressed locking means operable within said stud and projecting through one side thereof for engagement with the wall of said aperture thereby to lock said stud against separation from the socket and means pivoted upon the socket-engaging part for retracting said locking means thereby to permit separation of said stud from said socket.

7. A separable fastener comprising, in combination, a socket presenting a stud-receiving aperture, a cooperating stud having a socket-engaging member presenting a neck for engagement with the wall at one side of said stud-receiving aperture, a spring-pressed locking member assembled with said socket-engaging part for engagement with the wall at the opposite side of said aperture, and manually operable supporting means pivoted upon said stud to shift said locking member thereby to permit separation of said stud from said socket.
8. A separable fastener comprising, in combination, a socket presenting a stud-receiving aperture, a cooperating stud including a casing, a tubular socket-engaging member pivoted upon said casing, a spring-pressed locking member guided therein and presenting a cam-shaped fin for engagement with the periphery of said stud-receiving aperture, said locking member shiftable to permit entrance of said head in said aperture, shiftable to lock said head therein and shiftable by a tipping movement of said casing relative to said socket-engaging mem-
- ber to permit separation of said stud from said socket.
9. A three-side lock fastener comprising, in combination, a socket presenting a stud-receiving aperture surrounded by a non-re-silient wall, a cooperating stud having a socket-engaging shank portion presenting a neck at one side thereof for engagement with the wall surrounding the stud-receiving aperture, an axially shiftable locking member forming part of the fastener assembly and being presented through a slot in the shank opposite said neck to hold said neck in engagement with the wall of the aperture, thereby to prevent separation of the fastener by a pull exerted at three sides thereof and pull-operable means operatively connected to said locking member whereby said locking member may be shifted out of engagement with the wall of the socket to permit separation of the fastener, said pull-operable means also forming part of the fastener assembly.

In testimony whereof, I have signed my name to this specification.

FRED S. CARR.
